UNITED STATES PATENT OFFICE

CLARENCE E. PARKERTON, OF NEW MILFORD, CONNECTICUT, ASSIGNOR TO WARREN C. MERCIER, OF DANBURY, CONNECTICUT

HAT STRETCHING MACHINE

Application filed July 10, 1929. Serial No. 377,220.

This invention relates to a machine for stretching and shaping the felted cone for making hats, and has for an object to provide a machine which will facilitate the shaping and working of the hat cone to proper shape and size and whereby this operation can be secured more easily and performed more rapidly than the methods now generally in use.

10 With the foregoing and other objects in view the invention consists in certain novel features of construction, combinations and arrangements of parts as will be more fully disclosed in connection with the accompanying drawings.

In these drawings:

Fig. 1 is a side elevation of the machine with parts broken away to more clearly show the construction.

20 Fig. 2 is a transverse section substantially on line 2—2 of Fig. 1.

Fig. 3 is a rear view of one of the sections of the cone support.

25 Fig. 4 is a side elevation thereof with a portion broken away to more clearly show the construction.

Fig. 5 is a detail partially in section and partially in elevation of the operating means for the cone sections.

30 Fig. 6 is a top plan view of the operating cam.

Fig. 7 is a side elevation thereof, and

Fig. 8 is a partial side elevation and partial section of the rotary tip block and support therefor.

The improved machine illustrated comprises an upright conical support made of a plurality of sections 10, in the form shown

40 there being four of these sections, although the number may be varied as found desirable.

These sections are mounted for radial movement from and toward each other, and a convenient means for mounting them is in horizontal radially extending guide ways 11

45 mounted on a suitable support or base 12 supported at a desirable height by suitable legs 13. It is preferred that the guide ways 11 be cast in one piece as then they are always

50 maintained in proper relation to each other,

and they are secured to the base 12 by any suitable means such as screws or bolts 14. It is preferred that the guide ways 11 be of dove tail grooves, and the sections 10 are provided on their lower ends with dove tail ribs 15 to fit and slide in these grooves. The sections also each preferably have an upright strengthening rib 16. When the sections are mounted in their grooves and are located at their inner-most positions they form a substantially cone shaped support 55 for the hat cone 17 which is to be operated upon.

At the upper or smaller end of the cone support is a rounded and tapered block 18 which is so shaped as to fit the tip of the hat cone and support it. This block is carried by a suitable upright support or frame 19 mounted on the base 12 and which extends upwardly 60 within the conical support formed by the sections 10. The block is mounted on the frame or support 19 for rotary movements by any suitable means such as the screw or bolt 20. This block 18 in effect forms a continuation 65 of the cone support.

Automatic means is provided for continuous shifting of the sections 10 laterally toward and from each other to expand and contract the cone support when the device is 70 in operation. For this purpose there is an upright shaft 21 extending through an opening in the base 12 and guided for reciprocating movements in a bracket 22 secured to the under side of the base. Adjustably secured

on the shaft 21 is a tapered cam 23 and it is 75 preferably threaded on this shaft for adjusting movements and has openings 24 for insertion of a suitable tool for turning the block to adjust it on the shaft. After ad-

justment it may be secured in an adjusted position by the lock nut 25. The sections 10 are provided with walls 26 to engage the tapered surface 23 of the cam so that as the cam 80 is forced upwardly this surface will force the sections 10 outwardly to expand the conical support.

It will, of course, be apparent that the size of this support and the amount to which it is expanded will depend on the 85 movement and position of the cam 23. The 90 movement and position of the cam 23. The 95 movement and position of the cam 23. The 100

shaft 21 has a head or plate 27 resting on an eccentric cam 28 on a shaft 29 operated by any suitable drive 30 from a motor 31 or other suitable source of power. A spring 32 between the head 27 and bracket 22 tends to force the shaft downwardly and hold the head 27 in contact with the eccentric 28. Springs are also provided tending to move sections 10 of the conical support inwardly 5 to contract the support and also to retain the shoulders 26 in engagement with the cam 23. For this purpose tension springs 33 are provided, one connecting the two diametrically opposite sections of each pair. Thus with 10 four sections there are two of these springs connected to the ribs 16 of the diametrically opposite sections by any suitable means such as bolts 34.

In operation it will be apparent as the 20 shaft 29 is rotated the shaft 21 and cam 23 are reciprocated up and down under the action of the eccentric 28 and spring 32. Upward movements of the cam 23 reacting against the surfaces 26 on the sections 10 will 25 force these sections radially outward or laterally away from each other to expand the conical support, and as the cam 23 moves downwardly the springs 33 will draw these sections inwardly toward each other to contract the conical support. When the felted cone is removed from the copper cone in the 30 coner it is very much out of shape and lopsided and has to be worked to get it to proper shape and the fibres of the fur properly felted together. The operator places this hat cone indicated at 17 over the conical support with the block 18 fitting in and supporting the tip of the cone. He then grasps the lower edge 35 of the hat cone on opposite 35 sides of the conical support and pulls the cone down against the surface of the support at the same time turning the hat cone about a vertical axis with the block 18 which, as described above, is mounted for turning movements. Under this action the expansion and 40 contraction of the conical support stretches and shapes the hat cone bringing it to the desired size and shape and pressing and feltting the fibres firmly together, the stretching 45 action being indicated by the dotted lines in Fig. 1. It is also preferred to provide in the surface of the sections 10 of the conical support a series of spaced peripheral grooves 36 which tend to prevent the hat cone slipping 50 upwardly on the surface of the support as the support expands. It will be apparent that this device does mechanically the work that has been previously done by hand and 55 does it in a much quicker and more satisfactory manner with much less labor on the part of the operator.

Having thus set forth the nature of my invention, what I claim is:

65 1. In a machine for stretching and shaping

hat cones, a cone shaped support to receive the hat cone and comprising a plurality of laterally movable sections, a block at the small end of the cone to fit into the tip of the hat cone to support it and rotatable relatively to the movable sections, and means for laterally moving the sections of the support toward and from each other to vary the effective size of the cone. 70

2. In a machine for stretching hat cones, a plurality of radially extending guides, an upright conical support for the hat cone comprising a plurality of sections mounted for lateral movement in said guides, a block at the smaller end of the support forming a substantial continuation of the surface thereof to fit into the tip of the hat cone to support it, a cam reciprocable longitudinally of said support, means on said sections cooperating with the cam to shift the sections laterally outward, and means for reciprocating the cam. 75

80 3. In a machine for stretching hat cones, a base, radially extending guides carried by said base, an upright conical support for the hat cone comprising a plurality of laterally movable sections mounted in said guides, a block mounted for rotary movement relatively to said laterally movable sections at the small end of said support to fit in the tip of the hat cone, and means for reciprocating the sections of the support in said guides. 85

89 4. In a machine for stretching hat cones, a cone shaped support having in its surface a plurality of spaced circumferentially extending grooves, said support comprising a plurality of laterally movable sections, a block mounted at the smaller end of the support to fit in the tip of the hat cone and rotatable relatively to the movable sections, and means for simultaneously moving the sections laterally to stretch a hat cone on the support. 90

100 5. In a machine for stretching hat cones, a base, radially extending guides carried by said base, an upright conical support for the hat cone comprising a plurality of laterally movable sections mounted in said guides and provided in their surfaces with a plurality of spaced circumferentially extending grooves, a block mounted for rotary movement relatively to the movable sections at the small end of said support to fit in the tip of the hat cone, and means for reciprocating the sections of the support in said guides. 105

110 6. In a machine for stretching hat cones, a horizontal base, a plurality of radially extending guides on said base, an upright conical support for the hat cone comprising a plurality of upright sections mounted for lateral movements toward and from each other in said guides, an upright support enclosed by said sections, a block at the upper end of the conical support mounted for turning movements on said upright support and shaped to fit in the tip of the hat cone, an upright 115

120

125

130

reciprocable shaft, a cam on said shaft, means on the movable sections to engage said cam to shift the sections outwardly, springs tending to move the sections inwardly, and means for reciprocating the cam shaft.

5 In testimony whereof I affix my signature.

CLARENCE E. PARKERTON.
